UNITED STATES PATENT OFFICE.

FRANK S. CORNWELL, OF NEW YORK, N. Y.

DESIGN FOR A LAP DESK.

Application filed July 1, 1924. Serial No. 10,023. Term of patent 7 years.

To all whom it may concern:

Be it known that I, FRANK S. CORNWELL, a citizen of the United States, residing at #119 Washington Place, New York city, New York, have invented a new, original, and ornamental Design for a Lap Desk, of which the following is a specification, reference being had to the accompanying drawing, forming a part thereof.

The drawing is a view in perspective of a lap desk showing my new design.

I claim:

The ornamental design for a lap desk as shown.

FRANK S. CORNWELL.
